UNITED STATES PATENT OFFICE

114,695

DESIGN FOR A LAMP

Charles A. Christoph, Amarillo, Tex.

Application February 16, 1939, Serial No. 83,240

Term of patent 7 years

To all whom it may concern:

Be it known that I, Charles A. Christoph, a citizen of the United States of America, residing at Amarillo, in the county of Potter and State of Texas, have invented a new, original, and ornamental Design for a Lamp, of which the following is a specification, reference being had to the accompanying drawing, forming part thereof, wherein:

I claim:

The ornamental design for a lamp, as shown.

CHARLES A. CHRISTOPH.
